COMBINED NOZZLE AND COMB FOR HAIR DRYERS

Michael G. Vitetta, 311 Fenimore Road,
Mamaroneck, N.Y. 10543

Filed Nov. 12, 1973, Ser. No. 415,014

Term of patent 14 years

Int. Cl. D28—03

U.S. Cl. D86—10 F

FIG. 1 is a front elevational view of a combined nozzle and comb for hair dryers showing my new design;

FIG. 2 is a top plan view;

FIG. 3 is a side elevational view; and

FIG. 4 is a bottom plan view.

I claim:

The ornamental design of a combined nozzle and comb for hair dryers, as shown.
